Primary Examiner — Garth Rademaker*Assistant Examiner* — Melanie Pellegrini(74) *Attorney, Agent, or Firm* — Demirjian Law Offices; Sevag Demirjian(57) **CLAIM**

The ornamental design for a jewelry pendant, as shown and described.

DESCRIPTION

FIG. 1 is a front perspective view of a pendant showing my design;

FIG. 2 is a top plan view thereof;

FIG. 3 is a bottom plan view thereof;

FIG. 4 is a front elevational view thereof;

FIG. 5 is a back elevational view thereof;

FIG. 6 is a left side elevational view thereof; and,

FIG. 7 is a right side elevational view thereof.

The broken lines showing a portion of a chain in FIG. 1 illustrate environmental subject matter and form no part of the claimed design. All other broken lines illustrate portions of the jewelry pendant which form no part of the claimed design.
